SYRINGE PISTON

Charles A. Gray, 2334 Scott St., Hollywood, Fla.

Filed Apr. 22, 1965, Ser. No. 84,919

Term of patent 3½ years

(Cl. D83—12)

FIG. 4.

FIG. 5.

FIG. 2.

FIG. 1.

FIG. 7.

FIG. 3.

FIG. 6.

FIG. 1 is a front elevation of a piston, showing my new design;

FIG. 2 is an elevation thereof in a contracted position; FIG. 3 is a side elevational view of the piston shown in FIG. 1;

FIG. 4 is a top plan view thereof;

FIG. 5 is a cross section taken on line 5—5 of FIG. 1; FIG. 6 is the bottom plan view thereof; and

FIG. 7 is a modified embodiment of the piston shown in FIG. 1 broken away for convenience of illustration.

The broken lines shown in FIG. 2 are for purposes of illustration only.

I claim:

The ornamental design for a syringe piston, as shown and described.
